UNITED STATES PATENT OFFICE.

JOHN A. ZUBLIN, OF LOS ANGELES, CALIFORNIA.

PUMP PLUNGER.

Application filed November 11, 1924. Serial No. 749,132.

This invention relates to reciprocating pumps, and it relates particularly to those types of pumps employing cup attachments in the plunger thereof.

My invention while especially adapted for use in the oil industry is also useful for pumping of water and other fluids. Pumps of the class to which my invention relates comprises a barrel carried on the tubing and situated at the bottom of the well in which barrel a plunger is reciprocated. The plunger may comprise a body member to which cups are secured, these cups being secured either at the top or the bottom of the plunger or at both ends, the purpose of these cups being to prevent leakage around the plunger. A pronounced disadvantage of the present types of plunger using cup attachments is that the upper cup member carries the entire weight of the head of oil in the well. This means that the pressure thereagainst causes considerable friction between this upper cup and the barrel of the pump and results in a rapid wearing away of both plunger and barrel. Another disadvantage is that a cup situated at the upper end of a plunger is exposed and any sand or silt gravitating will collect and pack under pressure in the cup member causing it to bind and rapidly wear away. In other words, in the present types of reciprocating plunger employing cups, the cups are in no way protected. The use of cups on the lower end of a plunger is disadvantageous inasmuch as when the plunger is lifted from the barrel of the pump, as the body of the plunger is moved out of the barrel, the oil thereabove will rush into the space in the pump barrel created by the removing of the plunger. The oil rushing into the barrel at a terrific speed catches the lower cup members of the plunger and causes an instantaneous destruction thereto.

It is an object of this invention to provide a plunger having a cup attachment which is superior to the other plungers of this type inasmuch as the novel arrangement thereof lengthens the life of the cup members and increases the efficiency of the pump.

It is also an object of this invention to provide a plunger of this type having a cup attachment which is protected against excessive pressures and strains and protected from sand. I accomplish this by disposing

of the cup attachment between upper and lower protective means.

It is a further object of the invention to provide in a plunger of this character a unique construction of cup attachment which facilitates its disposal in the manner mentioned.

Other objects and advantages of the invention will be made evident hereinafter.

Referring to the drawings which are for illustrative purposes only,

Fig. 1 is a vertical sectional view through a pump embodying the features of my invention, the plunger of this pump being broken and contracted in various places in a manner to show the essentials thereof.

Fig. 2 is a section taken as indicated by the line 2—2 of Fig. 1.

Fig. 3 is a section taken as indicated by the line 3—3 of Fig. 1.

Fig. 4 is a fragmentary section taken on the line 4—4 of Fig. 1.

In the form of my invention shown in the drawings, I provide a pump barrel 11 which is suspended on tubing in a well in which pump barrel 11 a pump plunger 12 is reciprocable. The pump plunger 12 comprises an upper plunger member 13 and a lower plunger member 14 between which upper and lower plunger members a cup attachment 15 is connected. The upper plunger member 12 comprises an attachment member 17 having a pin 18 to which the lower socket 19 of a sucker rod string may be secured. A plunger body 21 is connected to the lower end of the body 17 by means of a threaded projection 22 which screws into an opening 23 of the attachment body 17.

Attached to the lower end of the upper plunger body 21 is a nipple 25 which threads into the chamber 26 of the body 21, as indicated at 27. The nipple 25 has a passage 28 therethrough which is arranged to be closed by a ball 24 in the chamber 26 and resting against the seat 29 provided by the upper end of the nipple 25. On the cylindrical portion 31 of the nipple 25 is placed a base portion 32 of an upper plunger sleeve 33. The external diameter of the plunger sleeve 33 is of such a size as to engage the inner wall of the barrel 11 having a fluid-tight relationship therewith.

On the threaded projection 36 of the nipple 25 is screwed a tubular body portion 37 of the cup attachment 15, this tubular body

37 having a head 38 into which the threaded projection 36 is extended. The upper face 39 of the head 38 engages with the lower face of the base 32 of the upper plunger sleeve 33, clamping it securely in place against the shoulder provided by the lower end of the body 21. Against an annular shoulder 40 of the tubular body 37 a cup 41 is placed, and alternately thereafter spacer members 42 and cups 41 are placed on the tubular portion 43 of the tubular body member 37. The cups 41 may be provided from any suitable material providing the desirable wearing qualities such as rubber or a composition cup. The spacer members 42 each have a central opening 45 through which the tubular portion 43 of the body 37 extends. An upper bevel face 46 of each of the spacers 42 engages with the lower face 25 of a lip 47 of an adjacent cup 40. A lower shoulder 48 of each of the spacers 42 is arranged to engage with the upper face of the lip 47 of an adjacent cup 40, this serving to clamp the cups 40 between the upper face 25 and the lower shoulder of the spacer members. On the lower end of the tubular portion 43 of the body 37 is secured a nut 50, this nut 50 having a recess 51 into which the lower end 52 of the tubular portion 43 is threadably secured. When the nut 50 is in place, it serves as a means for clamping the cups and spacers in their proper positions.

On the lower threaded projection 53 of the nut 50 there is screwed a flexible joint body 54, this body 54 having a recess 55 into which the projection 53 extends. A securing pin 56 extends through an opening 57 provided in the lower portion 58 of the body 54, this pin 56 having a T head 59 which engages with the upper face 60 of the portion 58. The body 54 has an opening 61 which connects through an opening 62 in the nut 50 with a central passage 63 of the tubular body 37, this passage 63 in turn connecting with the opening 28 in the nipple 25. The shaft portion 64 of the pin 56 threads into an opening 65 situated in the upper end of a lower plunger member body 66. This lower plunger member body 66 is of the same construction as the upper plunger body 21 having a chamber 67 into which the upper threaded end 68 of a lower nipple 69 is threaded. A ball 70 is arranged, as shown, to rest on the upper face 71 of the nipple 69 in a manner to close the passage 72 therethrough. A lower nut 73 is secured on the lower end 74 of the nipple 69, this lower nut 73 having a recess 75 into which the portion 74 of the nipple 69 threads. The nut 73 serves as a means for securing a lower plunger sleeve 77 in place, this plunger sleeve 77 having a base 78 which is clamped between the lower face 79 of the lower plunger body 66 and the upper face 80 of the 73. Extending upwardly from the base

78 is a sleeve portion 82, the outer face of this lower plunger sleeve being of such a size as to contact with the inner face of the barrel 11 having fluidtight engagement therewith. This plunger 12 is arranged to be reciprocated in the barrel 11 through a string of sucker rods which extends from the surface of the well.

During the downward travel of the plunger 11, the balls 24 and 70 are removed from their seats and oil is allowed to flow upwardly into and above the plunger, this oil passing through the opening 72 in the lower nipple 69, through the chamber 67 into the interior of the lower plunger sleeve 77, and through the opening in the flexible joint body 54. It then passes through the openings 62, 63 and 28 past the ball 24 and into the chamber 26 of the body 21. The oil passes from the chamber 28 to the interior of the upper sleeve 32 and from thence passes into the pump tubing 86. During the upward travel of the plunger 11, the oil is lifted.

The weight of the oil is carried entirely by the upper and lower sleeve members as long as a fluidtight relationship between the sleeve members and the barrel exists. When a slight leakage occurs in the upper plunger sleeve 33, the cup attachment 15 is called upon to prevent leakage of the pump and even under these circumstances, the weight thereon will be very small. Any sand which gravitates from the oil collects entirely in the sleeve members 33 and 77, and not in the cups 41. This is because of the fact that the cups 41 are not in direct contact with the oil flowing through the plunger.

From the drawings and description, it will be seen that in the construction shown, the cup attachment 15 is protected entirely against strains and from sand by the upper plunger member 12. The lower plunger member 14 serves as a protection for the cup attachment 15 when the plunger is being removed from the barrel 11. In pumps having cup attachments, but not having a lower member as does my invention, the oil above the plunger will rush violently into the barrel as the body portion of the plunger moves from the barrel. Oil rushing into the barrel catches the cups in a manner to immediately damage them and unfit them for future use. In my construction when the plunger is removed from the barrel, the inrush of oil will not occur until the lower plunger member 14 moves from the barrel 11. The cup attachment 15 is at this time a considerable distance above the barrel and will not be affected by the rushing of the oil into the space in the member created by the removing of the plunger. Practical experience has proven that the same kind of cups which previously lasted for a period of about two weeks in the old

types of pump may be used four times as long in a plunger of my invention.

It is plainly obvious from the drawing that the lower plunger section is flexibly or hingedly connected to the cup attachment in such a manner that it may adjust itself laterally in the pump barrel, but independently of the cup attachment. There is, however, no relative axial movement between the cup attachment and the pump shaft. It is highly desirable to have this lateral adjustment so that the cup attachment and the plunger section can individually align themselves in the pump barrel, since the pump barrel is sometimes crooked.

I claim as my invention:

1. A reciprocating pump comprising: a pump barrel; and a plunger reciprocable in said barrel, said plunger consisting of a section having a plunger sleeve and means secured to said section for providing a fluid-tight relationship between said barrel and said plunger so that it is only laterally adjustable relative to said means.
2. A reciprocating pump comprising: a pump barrel; and a plunger reciprocable in said barrel consisting of an upper section, a lower section, and means connected between said sections and flexibly connected to one of said sections for contacting said barrel so as to provide a fluidtight relationship therebetween.
3. A reciprocating pump comprising: a pump barrel; and a plunger reciprocable in said barrel consisting of a section having a plunger sleeve and a cup attachment flexibly secured to said section, both said section and said cup attachment being adapted to have engagement with said pump barrel.
4. A reciprocating pump comprising: a pump barrel; a pump plunger reciprocable in said barrel consisting of an upper plunger member; means rigidly secured to said upper plunger member for wiping said barrel when said plunger reciprocates; and a lower plunger member flexibly secured below said means.
5. A reciprocating pump comprising: a pump barrel; and a plunger reciprocable in said barrel consisting of cup members en-

gaging said barrel, upper protecting means arranged above said cup members, and lower protecting means having a sleeve flexibly arranged below said cup members so as to be laterally adjustable relative to said cup members.

6. A reciprocating pump comprising: a pump barrel; and a plunger reciprocable in said barrel consisting of an upper plunger member, a lower plunger member and means connecting between said plunger members for wiping said barrel when said plunger reciprocates, said means being flexibly connected to one of said plunger members.

7. A reciprocating pump comprising: a pump barrel; and a plunger reciprocable in said barrel consisting of an upper plunger member, a cup attachment rigidly secured to the lower end of said upper plunger member; and a lower plunger flexibly secured to the lower end of said cup attachment.

8. A pump as set forth in claim 7 in which said cup attachment comprises: a tubular body; cup members arranged on said tubular body; and spacer members arranged on said body for spacing said cup members.

9. In a reciprocating pump of the class described, the combination of a plunger comprising: an upper plunger member; a lower plunger member; a tubular body rigidly secured to one of said plunger members; cup members carried by said tubular body; and spacer members arranged on said tubular body for spacing said cup members.

10. In a reciprocating pump of the class described, the combination of a plunger comprising: an upper plunger member; a tubular body rigidly secured to said upper plunger member; cup members carried by said tubular body; spacer members arranged on said tubular body for spacing said cup members; a lower plunger member; and means for flexibly securing said lower plunger member to said tubular body.

In testimony whereof, I have hereunto set my hand at Los Angeles, California, this 5th day of November, 1924.

JOHN A. ZUBLIN.
